(57) **ABSTRACT**

A new distinct variety of grapevine plant named 'ARD46' abundantly forms attractive meaty seedless berries with a red skin coloration, lax and large clusters which display a Labrusca flavor, the fruit commonly is ready for harvesting during July-August in San Joaquin Valley of Central California, U.S.A., and displays good eating qualities as a table grape having a fruit firmness which renders the fruit well amenable for handling, shipping, and storage.

1 Drawing Sheet

1

Classification: The present invention relates to a new *Vitis vinifera* Grapevine.

Varietal denomination: The new Grapevine plant has a varietal denomination 'ARD46'.

BACKGROUND OF THE INVENTION

A breeding program was initiated during the late 1990's near Bakersfield in San Joaquin Valley of Central California. In 2016, during this breeding program, a new variety of *Vitis vinifera* was created by deliberate cross breeding of two parent plants by emasculation of the pollen bearing organ of the female and introducing pollen from another male origin. The female parent of the new variety was 103C-57+2 which is a crispy and juicy white seedless variety, with a natural sweet flavor (non-patented in the United States). The male parent (i.e. the pollen parent) of the new variety was 26-6+3, a fertile and crunchy seedless white variety (non-patented in the United States).

TABLE 1

'ARD46' compared with parents & closely related variety:				
	'ARD46'	103C-57+2	26-6+3	Flame Seedless
Berry texture	Meaty	Crispy and Juicy	Crunchy	Crisp
Berry shape	Broad Ellipsoid	Broad Ellipsoid	Ovoid	Globose
Cap	Thick/Medium	Medium/short	Medium/ Medium	Thick/Short
stem/brush				

2

The parentage of the new variety can be summarized as follows: 103C-57+2 X 26-6+3

An artificial pollination was created, and the result was an embryo which possessed unique genetic qualities. The rudiments resulting from the above pollination were embryo rescued.

In 2017 the plant was transplanted to Bakersfield in San Joaquin Valley of Central California.

It was found that the new grapevine of the present invention possesses the following combination of characteristics:

- (a) Forms attractive meaty seedless berries with a red skin coloration; in lax and large clusters which display a Labrusca flavor,
- (b) Commonly bears fruit during the month of July-August in the San Joaquin Valley of Central California, U.S.A.,
- (c) Bears fruit that is firm and is well amenable for storage, handling, and shipping, and
- (d) Produces 38 bunches per vine, and an average of about 2 banches per shoot, at a total of 51 lbs. fruit per vine.

The new variety during observation to date has displayed no visible disease, and has displayed an ability to well resist cold, drought, heat; but sensitive to direct exposure to sun and wind. The fruit of the new variety has been found to display excellent handling and shipping qualities combined with desirable dessert eating qualities.

The new variety of the present invention has been found to undergo asexual propagation beginning in 2018 near Bakersfield in the San Joaquin Valley of Central California, U.S.A. by bud grafting on mature Thompson seedless root-

stock (non-patented in the United States). Such asexual propagation has been conducted thereafter in successive years to date and has shown that the characteristics of the new variety are strictly transmissible from one generation to another. Accordingly, the new variety undergoes asexual propagation in a true to type manner.

SUMMARY OF THE INVENTION

The new variety 'ARD46' is a red seedless table grape with a high production, e.g., about 38 bunches per vine, and an average of about 2 bunches per shoot.

Asexual reproduction by micro propagation of the new variety as performed near Bakersfield, Calif., U.S.A., shows that the forgoing and other distinguishing characteristics come true to form and are established and transmitted through succeeding propagations.

BRIEF DESCRIPTION OF THE DRAWING

The accompanying photographic illustration shows typical six-year-old specimens of the new variety, vegetatively propagated, in color as nearly true as it is reasonably possible to make in a color illustration of this character. Colors in the photograph may differ from the color values cited in the detailed botanical description below, which accurately describes the colors of the new Grapevine.

FIG. 1 shows leaves, stems, tendrils, and grapes of 'ARD46'.

DETAILED BOTANICAL DESCRIPTION

The chart used in the identification of colors is The RHS Colour Chart of The ROYAL HORTICULTURAL SOCIETY (3rd Edition). The description is based on the observation of plants growing on Thompson Seedless' rootstock outdoors near San Joaquin Valley of Central California, U.S.A.

TABLE 2

VINE CHARACTERISTICS:

Vigor	Vigorous upright shoots
Productive capacity	Bearing at a natural, average capacity. Spur pruning.
Trunk	Strong and developed. Diameter is 2 inches, at 9.5 inches above ground. Rough with a fibrous, shaggy exterior. Light brown coloring - Greyed orange 177B

Date of bud burst in Bakersfield Calif.: February 26th.

TABLE 3

YOUNG SHOOT CHARACTERISTICS:

Openness of tip	Fully open
Density of prostrate hairs on tip	Medium
Anthocyanin coloration of prostrate hairs on tip	Red purple 59A
Density of erect hairs on tip	Medium

TABLE 4

YOUNG LEAF CHARACTERISTICS:

5	Color of upper side of blade	Yellow green 152A
	Color of lower side of blade	Yellow green 152B
	Density of erect hairs between main veins on upper side of blade	Absent or very sparse
	Density of erect hairs between main veins on lower side of blade	Sparse
10	Density of prostrate hairs on main veins on upper side of blade	Dense
	Density of prostrate hairs on main veins on lower side of blade	Medium

TABLE 5

SHOOT CHARACTERISTICS:

15	Attitude (before tying)	Semi-erect
	Color of dorsal side of internodes	Greyed red 178A
	Color of ventral side of internodes	Yellow green 146D
	Color of dorsal side of nodes	Greyed red 178B
	Color of ventral side of nodes	Yellow green 146D
20	Density of erect hairs on internodes	Sparse
	Density of prostrate hairs on internodes	Sparse
	Length of tendrils	4.3 inches
	Diameter of tendrils	0.06 inches
	Color of tendrils	Yellow green 144B
	Number of tendrils at bloom	5
	Positioning of first flowering and fruiting node	The first bunch is in the 3rd node
25	Inflorescence number per flowering shoot	2

TABLE 6

FLOWER CHARACTERISTICS:

35	Reproductive organs	Fully developed stamens and fully developed gynoecium
	Flower length	0.3 inches
	Flower diameter	0.17 inches
	Pistil length	0.14 inches
	Pistil color	Yellow green 144A
	Pollen Amount	Rich
	Pollen color	Yellow 11B
	Stamen color	Yellow green 145C
	Stamen length	0.15 inches
40	Number of stamen	6

First bloom in Bakersfield, Calif.: April 15th.

Date of full bloom in Bakersfield, Calif.: April 22nd.

TABLE 7

MATURE LEAF CHARACTERISTICS:

55	Size of blade	6 inches x 6 inches
	Shape of blade	Pentagonal
	Base descriptors	Pentagonal
	Leaf margin	Serrate
	Leaf apex	Acute
	Blistering of upper side of blade	Absent or very sparse
	Depth of upper lateral sinuses	Shallow
	Number of lobes	Five
60	(Only varieties with lobed leaves)	Closed
	Arrangement of lobes of upper lateral sinuses	
	Arrangement of lobes of petiole sinus	Half open
	Length of teeth	0.38 inches
65	Ratio length/width of teeth	Small

TABLE 7-continued

MATURE LEAF CHARACTERISTICS:	
Shape of teeth	Mixture of both sides straight and both sides convex
Density of prostrate hairs between main veins on lower side of blade	Absent or very sparse
Density of erect hairs on main veins on lower side of blade	Absent or very sparse
Density of erect hairs between the main veins on upper side of blade	Absent or very sparse
Density of prostrate hairs on main veins on upper side of blade	Absent or very sparse
Length of petiole compared to length of middle vein	Much shorter
Top side color	Green 137A
Bottom side color	Yellow green 146B
Texture of upper side of blade	Rough
Texture of lower side of blade	Little Rough
Vein color on upper blade	Yellow green 146C
Vein color on lower blade	Yellow green 145C
Venation pattern for upper blade	Netlike venation
Venation pattern for lower blade	Netlike venation
Petiole length	2.75 inches
Petiole diameter	0.11 inches
Petiole color	Yellow green 152A
Petiole texture	Rough
Mature leaf anthocyanin coloration of main veins upper surface	Strong (Red purple 58A)

Date of beginning of berry ripening in Bakersfield Calif.:

July 15th.

TABLE 8

BUNCH CHARACTERISTICS:	
Size (peduncle excluded)	Large
Density of berries on bunch	Lax
Bunch length	9.5 inches
Bunch diameter	5.5 inches
Length of peduncle of primary bunch	0.75 inches
Diameter of peduncle of primary bunch	0.14 inches
Peduncle of primary bunch color	Yellow green 145B
Peduncle texture	Smooth
Bunches per vine	38
Average bunch weight	1.3 lbs

TABLE 9

BERRY CHARACTERISTICS:	
Size	Medium
Length	1 inch
Weight	0.24 oz
Diameter	0.8 inches
Shape	Broad ellipsoid
Color of skin (without bloom)	Red 53A
Flesh color	Yellow green 145D
Brix	20.1
Titratable acidity percentage	0.25%
Juice	4.1 pH
Ease of detachment from pedicel	Moderately easy
Thickness of skin	Medium
Anthocyanin coloration of flesh	None
Firmness of flesh	Moderately firm
Particular flavor	Foxy
Formation of seeds	None
Berries per bunch	132
Juiciness of Berry Flesh	Juicy

TABLE 10

PEDICEL CHARACTERISTICS:	
5	Length 0.35 inches
	Diameter 0.09 inches
	Color Yellow green 145C
	Pedicel texture Rough

TABLE 11

WOODY SHOOT CHARACTERISTICS:	
10	Woody shoot texture Rough
	Woody shoot color Greyed orange 165A
	Woody shoot length 60 inches
	Diameter 0.25 inches
	Internode length 2.9 inches

Market use of observed plants: Fresh market.

20 AGE AND GROWING CONDITIONS
Six years growing under Y system in South Joaquin Valley (hot, dry summers).

SHIPPING CHARACTERISTICS

30 Fruit was in cold storage. Stored in poly bags inside polystyrene boxes with sulfur pads. After 60 Days: rachises were 80% green; 0% berry shattering; no berry wrinkling or cracks were apparent.

DNA PROFILE

35 To further characterize the new variety DNA was extracted from plant samples and a DNA profile was obtained at California Seed & Plant Lab, California USA using base pairs for 10 standard microsatellite DNA markers. The data is presented hereafter.

TABLE 12

DNA profile for 'ARD46'		
	Microsatellite DNA Marker	Allele Sizes in Base Pairs
50	M 1	228 234
	M 2	239 239
	M 3	185 194
	M 4	212 212
	M 5	253 257
	M 6	123 135
	M 7	189 189
	M 8	255 255
	M 9	214 214
55	M 10	221 233

60 The 'ARD46' variety has not been observed under all possible environmental conditions to date. Accordingly, it is possible that the phenotypic expression may vary somewhat with changes in light intensity and duration, cultural practices, and other environmental conditions.

65 Additional information relating to plant and fruit disease and pest resistance or susceptibility has not been observed to date. Specification of the plant hardiness zone and the heat/cold resistance has not been observed to date.

What is claimed is:

1. A new and distinct grapevine plant, botanically known as *Vitis vinifera*, identified as 'ARD46', substantially as shown and described herein.
